COMBINED TOY TUGBOAT AND BARGE

Robert Y. Allen and Melvin Shaw, Los Angeles, Calif.,
assignors to Hoover Products, Inc., Youngstown, Ohio,
a corporation of Ohio

Filed July 13, 1960, Ser. No. 61,340

Term of patent 14 years

(Cl. D34—15)

FIG. 1

The bottom of the toy is substantially plain.

We claim:

The ornamental design for a combined toy tugboat and barge, as shown and described.
